Patented Feb. 6, 1917.

UNITED STATES PATENT OFFICE.

FRED S. CARR, OF BROOKLINE, MASSACHUSETTS, ASSIGNOR TO CARR FASTENER COMPANY, OF CAMBRIDGE, MASSACHUSETTS, A CORPORATION OF MAINE.

CARTRIDGE-CARRIER.

1,214,895.

Specification of Letters Patent.

Patented Feb. 6, 1917.

Application filed July 21, 1916. Serial No. 110,585.

To all whom it may concern:

Be it known that I, FRED S. CARR, a citizen of the United States, residing at Brookline, in the county of Norfolk and State of Massachusetts, have invented new and useful Improvements in Cartridge-Carriers, of which the following is a specification.

This invention relates to carriers for containing cartridges coupled together by clips, the carrier being adapted to contain two or more clips side by side, and each clip containing a plurality of cartridges.

The type of carrier to which my invention relates includes a series of flexible pockets usually of woven fabric formed on and connected by a belt adapted to be secured to a soldier's body, each pocket having an open mouth at its upper end, and a flexible flap attached to the back side of the pocket and having a neck portion which extends across the mouth of the pocket and an end portion which overlaps the outer side of the pocket, means being provided for detachably securing said end portion to the pocket. The normal shifting of the flap from its covering to its uncovering position involves a swinging movement of its outer end outward and upward from the front of the pocket to a point above the pocket mouth.

The object of the invention is to positively prevent the above-mentioned normal shifting of the flap by accident and render practically impossible the unfastening of the flap by forces tending to shift it in the normal direction, thus preventing liability of the accidental unfastening and displacement of the flap, and the loss of cartridges contained in the pocket, the object being to permit the convenient manual unfastening and displacement of the flap to permit the insertion and removal of cartridges.

In accordance with the invention I preferably employ as the fastening means a stud-and-socket fastener of the type shown by Letters Patent No. 1,038,288, dated September 10, 1912, said fastener comprising a stud member attached to the outer side of the pocket and a socket member attached to the flap and adapted to receive the stud member.

The members of said fastener are provided with complementary interengaging parts which are separable by a tipping movement of the socket member in one direction relatively to the stud member, and

are practically inseparable by tipping movements of the socket member in any other direction.

In accordance with my invention I preferably secure the stud member to the outer side of the pocket and suitably connect the socket member with the holder to cause its coöperation with the stud member when the flap is closed. I also so arrange the socket member that the tipping movement whereby the members are separated is one which moves the end of the socket member nearest the neck portion of the flap outwardly and downwardly from said neck portion, and abnormally bends or bulges a part of the end portion without moving the said portion bodily outward from the pocket. The members are inseparable by a tipping movement of the socket in any other direction, so that the members cannot be separated by strain on the lower or transverse edge of the flap tending to normally shift the flap from its closed to its open position, or by strain on either of the vertical edges of the flap tending to swing the flap outward horizontally. Provision is therefore made for preventing the accidental opening of the flap by any strain liable to be exerted on its transverse lower edge or on either of its vertical edges with any obstacle or displacing instrumentality. To permit the predetermined separating tipping movement of the socket member I connect with it a tab or handle which is arranged to be grasped by the operator and impart said predetermined tipping movement to the socket member, said tab furnishing a convenient finger grip or engaging means not afforded by the flap itself, when the pocket is charged.

Of the accompanying drawings forming a part of this specification:

Figure 1 represents a perspective view of a portion of a cartridge carrier, said portion embodying my invention;

Fig. 2 represents a section on line 2—2 of Fig. 1;

Fig. 3 represents a section on line 3—3 of Fig. 1;

Fig. 4 represents a section on line 4—4 of Fig. 3;

Fig. 5 represents a front view of a portion of a cartridge carrier, and illustrates another embodiment of the invention;

Fig. 6 represents a section on line 6—6.

by the normal shifting movement of the flap is positively prevented when said members are interengaged.

2. In a cartridge carrier, in combination, 5 a flexible pocket, a cover formed as a flexible flap attached to the rear side of the pocket, and having a neck portion adapted to extend across the pocket mouth, and an end portion adapted to overlap the outer side of the 10 pocket, the normal shifting of the flap from its closed to its open position involving a swinging movement of its outer end outward and upward from the front of the pocket to a point above the pocket mouth, comple- 15 mental inner and outer fastening members adapted to positively prevent said normal shifting, the inner member being attached to the pocket and the outer member movable relatively to the inner member to effect dis- 20 engagement, said members being provided with interengaging parts adapted to confine the flap in its closed position, separable by an endwise tipping movement of the outer member outwardly and downwardly from 25 the neck portion of the flap, and inseparable by an opposite endwise tipping movement of the outer member, whereby the normal shifting movement of the flap is positively prevented when said members are inter- 30 engaged, and a flexible handle attached to the outer member and adapted to be pulled in the direction required to tip said member outwardly and downwardly from the neck portion of the flap.
3. In a cartridge carrier, in combination, 35 a flexible pocket, a cover formed as a flexible flap attached to the rear side of the pocket, and having a neck portion adapted to extend across the pocket mouth, and an end portion adapted to overlap the outer side of the 40 pocket, the normal shifting of the flap from its closed to its open position involving a swinging movement of its outer end outward and upward from the front of the 45 pocket to a point above the pocket mouth,

and complementary inner and outer fastening members adapted to positively prevent said normal shifting, the inner member being attached to the pocket and the outer member attached to the flap, said members being provided with interengaging parts adapted to 50 confine the flap in its closed position, separable by a tipping movement of the outer member requiring an abnormal bending or bulging of the upper portion of the flap, and 55 inseparable by an opposite tipping movement of the outer member requiring a normal movement of the flap.

4. In a cartridge carrier, in combination, 60 a flexible pocket, a cover formed as a flexible flap attached to the rear side of the pocket, and having a neck portion adapted to extend across the pocket mouth, and an end portion adapted to overlap the outer side of the pocket, the normal shifting of the flap 65 from its closed to its open position involving a swinging movement of its outer end outward and upward from the front of the pocket to a point above the pocket mouth, complementary inner and outer fastening 70 members adapted to positively prevent said normal shifting, the inner member being attached to the pocket and the outer member attached to the flap, said members being provided with interengaging parts adapted to 75 confine the flap in its closed position, separable by an abnormal movement of the outer member requiring an outward bending or bulging of the upper portion of the flap, and 80 inseparable by an opposite tipping movement of the outer member, and a flexible handle attached to the outer member and flap and located between said member and the neck whereby the upper portion of the flap may be abnormally moved and the outer 85 member tipped outwardly and downwardly from the neck portion of the flap.

In testimony whereof I have affixed my signature.

FRED S. CARR.
